FIREPLACE SCREEN

Daniel K. Eisele, Philadelphia, Pa.

Application September 30, 1937, Serial No. 166,505

7 Claims. (Cl. 126—202)

This invention has to do with screens such as are commonly employed in conjunction with fireplaces for the purpose of guarding against the escape of sparks, flying embers and other undesirable matter from the fireplace.

The present invention has in view as its foremost objective the provision of a metallic screen for a fireplace which is made up of two screen parts that are relatively movable into closed or open positions.

Associated with this phase of the invention an important objective is the provision of improved means for mounting the screen parts in the fireplace in such a manner as to accommodate their relative movement. In carrying out this idea in a practical embodiment the invention has in view the use of a cross bar as a means for slidably supporting the screen parts.

Another somewhat more detailed object of the invention is the provision of means for causing the sliding movement of the screen parts. In accordance with this invention a chain is mounted over pulleys and connected with the screen parts in such a manner that by pulling upon one end of the chain the screen parts will open, while a pull exerted on the other end of the chain will cause a closing movement of the screen parts.

Still another object of the invention is the provision of means for mounting the screen parts in a fireplace whereby the mounting and operating parts of the screen are rendered substantially invisible. This idea is carried out by forming a groove in the top wall of the fireplace which is lined with an appropriate channel bar; the supporting rod for the screen including the pulleys, and the mechanism associated with the chains being disposed in the channel of the channel bar whereby they are substantially invisible from the front of the fireplace.

Various other more detailed objects and advantages of the invention will in part become apparent and in part be hereinafter stated, as the description of the invention proceeds.

The invention, therefore, comprises a fireplace screen that includes a pair of screen parts that are relatively movable. These screen parts are slidably mounted on a bar that is adapted to extend transversely across the front opening of a fireplace. A chain and an associated pulley arrangement are associated with the screen parts and bar to provide for the relative movement thereof.

For a full and more complete understanding of the invention, reference may be had to the fol-

lowing description and accompanying drawings, wherein

Figure 1 is a front view of a fireplace having a screen applied thereto in accordance with the precepts of this invention.

Figure 2 is a vertical section through the fireplace shown in Figure 1; this view being taken on a plane at right-angles to the showing of Figure 1.

Figure 3 is a view of a modification in which the channel structure for receiving the supporting bar is eliminated.

Figure 4 is an enlarged detailed view of the upper portion of the screen parts and the supporting bar therefor.

Figure 5 is an enlarged detailed view bringing out the arrangement for supporting the screen parts at the sides of the fireplace.

Figure 6 is an enlarged detailed view in perspective of one of the sliding plates to which the edges of the screen parts are anchored, and

Figure 7 is a detailed elevational showing of one of the pulley mechanisms that are carried by the supporting bar.

Referring now to the drawings, wherein like reference characters denote corresponding parts, a fireplace is shown in Figure 1 as including a front opening that is defined by side walls 10 and 11 and a top wall 12. Ordinarily fireplaces of this type are made from brick or a similar material, and in a preferred embodiment of the invention the top wall 12 has the bricks cut away to provide a groove 13 that extends transversely across the top wall just a slight distance back from the front face of the fireplace; this relationship being brought out in Figure 2.

A channel bar designated 14 is snugly received in the groove 13 and constitutes a lining therefor. This channel bar 14 may be made of any desired material, and is illustrated as having flanges 15 which engage the top wall 12 on opposite sides of the groove 13.

The supporting bar for the screen may be mounted within the channel of the channel bar 14, or this channel may be entirely eliminated, as shown in Figure 3. In any event, the cross bar will take the form clearly shown in Figure 4, and which is referred to generally by the reference character B. At each end the bar B is formed with cylindrical portions 16 which are securely received in anchoring elements 17 (Figure 3) that are in turn affixed to the side walls 10 and 11 as by the plate and bolt construction represented at 18.

Intermediate the cylindrical section 16 the bar

B is of a rectangular formation designated 19. At this point it is well to note that the cylindrical section 16 at the left hand side of the showing of Figure 4 carries a bracket member 20 which in turn carries a pulley 21 that is rotatable therein. The cylindrical section 16 at the other, or right hand side of the showing of Figure 4, carries a bracket member 22 that in turn carries a pair of pulleys 23 and 24 (see Figure 7). The purpose of these pulleys will be pointed out hereinafter.

Slidably received on the bar B are a pair of plate elements designated P₁ and P₂. These plate members P₁ and P₂ are of a duplicate complementary construction, and only one of them needs be described in detail for the purpose of this specification.

Accordingly, upon reference to Figure 6 it will be noted that the plate member P₁ comprises a rectangularly shaped casing 25 that is disposed about the correspondingly shaped portion 19 of the bar B and is slidable thereon. At one end one side wall, and portions of the top and bottom walls of the casing 25, are continued to define a channel construction identified at 26 which fits about one side of the rectangular part 19 of the bar B.

At this point it is well to note that the constructions 25 and 26 of the plates P₁ and P₂ are complementary so as to permit these plates to slide into an overlapping position.

Connected to the underside of the casing 25 and channel 26, as by a flange represented at 27, is a plate 28 that is formed with a plurality of openings 29, for a purpose to be later described. Extending downwardly from the free edge of the channel construction 26 is a plate extension 30 that extends to the bottom of the fireplace opening.

40 A pair of screen parts are shown in Figure 4 and are identified as S₁ and S₂ respectively. The screen part S₁ has one corner thereof anchored to the plate assembly P₁, with the free or inner edge of the screen part S₁ connected to the plate extension 30, as shown at 31 in Figure 4. The side of the screen part S₁ which is disposed adjacent to the side wall 10 of the fireplace includes a rod 32 which imparts rigidity whereby the side edge of the screen is definitely defined, and immediately adjacent to the rod 32 the mesh of the screen S₁ carries a supporting ring 33 that is fitted over the cylindrical part 16 of the bar B. In this position the bracket 20 precludes the possibility of the ring 23 sliding along the bar, and the inner edge of the screen part S₁ is thus held against movement.

60 Each of the screen parts S₁ and S₂ may be of any desired construction, but the invention has particularly in mind a wire or metallic mesh which has the desired property of flexibility to readily accommodate opening and closing of the screen. This wire mesh should be, of course, effective to provide the desired protective effects.

Between the plate P₁ and the bracket 20 the screen part S₁ may be supported by as many supporting rings as are found necessary; the number of these rings being dependent upon the length of the bar B. These rings are identified generally as R, and are similar in construction to the ring 33, being provided with hook portions 34 which engage with the mesh of the screen parts S₁ and S₂.

The screen part S₂ has its upper corner anchored to the plate P₂ in the same manner as above described in connection with the screen

part S₁. This screen part S₂ also has its corner at the outer edge connected to the plate extension 30 of the plate extension P₂, and the side edge of the screen part S₂ which is adjacent to the wall 11 of the fireplace is supported by a ring that is identical in all respects to the ring 33. 5

A chain, which is represented somewhat diagrammatically in the showing of Figure 4 and designated 35, passes over the pulley 23 that is carried by the bracket 22 and through the supporting rings R that are associated with the screen part S₂. This chain then passes through the openings 29 in the plate P₂ in the manner shown in Figure 4 and which passage constitutes, in effect, an anchorage of the chain to the member 28 of the plate assembly P₂. This chain 35 is then continued through the rings R that are associated with the screen part S₁ and around the pulley 21 and thence back through the rings R to the member 28 of the plate assembly P₁, 10 where it is passed through the openings 29 in the same manner as in the plate assembly P₂. 15

The chain is then continued on through the rings R of the screen part S₂ and over the pulley 21 to a convenient position; each of the extremities of the chain being provided with any desired operating members, such as that shown in Figure 6, to facilitate grasping thereof.

By grasping the operating member 36 that is shown in Figure 4, and exerting a pull thereon 30 the two parts S₁ and S₂ will be drawn together, and by releasing this end of the chain and exerting a pull on the other end of the chain the screen parts S₁ and S₂ may be drawn apart.

While preferred specific embodiments of the 35 invention are hereinbefore set forth it is to be clearly understood that I am not to be limited to the exact construction illustrated and described, because various modifications of these details may be provided in putting the invention into 40 practice within the purview of the appended claims.

I claim:

1. A fireplace screen of the character described comprising a supporting bar adapted to be 45 mounted in a fireplace opening, a pair of plate assemblies slidably mounted on said supporting bar, a pair of screen parts each having one corner affixed to said plate assemblies, plate extensions extending downwardly from each of said plate 50 assemblies, each of the screen parts having an edge secured to said plate extensions, the edges of said screen parts which are remote from said plate assemblies being immovably affixed to said supporting bar, and means for moving said plate 55 assemblies along the bar to impart opening and closing movements to the screen parts.

2. A fireplace screen of the character described comprising a supporting bar adapted to be 60 mounted transversely across the upper part of a fireplace opening, a pair of complementary supporting plates slidably mounted on the bar, said supporting plates being movable on the bar and adapted to assume an overlapping position, plate extensions extending downwardly from said plate 65 assemblies substantially to the bottom of the fireplace, a pair of screen parts each having one edge connected to said plate extensions, with the corner at the upper part of said edge connected to the plate assemblies, means for supporting the 70 edges of said screen parts remote from the plate extensions from the supporting bar, said means also constituting a means for holding said edges against movement along the bar, supporting rings associated with each screen part for supporting 75

the screen part from the bar, said rings being slidable along the bar, and means for causing relative movement of the plate assemblies.

3. A fireplace screen of the character described comprising a supporting bar adapted to be mounted transversely across the upper part of a fireplace opening, a pair of complementary supporting plates slidably mounted on the bar, said supporting plates being movable on the bar and adapted to assume an overlapping position, plate extensions extending downwardly from said plate assemblies substantially to the bottom of the fireplace, a pair of screen parts each having one edge connected to said plate extensions, with the corner at the upper part of said edge connected to the plate assemblies, means for supporting the edges of said screen parts remote from the plate extensions from the supporting bar, said means also constituting a means for holding said edges against movement along the bar, supporting rings associated with each screen part for supporting the screen part from the bar, said rings being slidable along the bar, pulleys carried by the bar at each end, and a chain passing over said pulleys and anchored to said plate assemblies for causing movement thereof along the bar.

4. In a fireplace screen of the character described and in combination, a supporting bar having cylindrical end sections and a rectangularly shaped body portion, and a pair of complementary plate assemblies slidable on said rectangularly shaped portions into an overlapping relationship, each of said plate assemblies including a channel construction for receiving a part of said bar, said plate assemblies being adapted to have the corners of flexible screen parts secured thereto.

5. In a fireplace screen of the character described and in combination, a supporting bar having a square shaped main body portion, means at each end of the bar for anchoring the same in position in the opening of a fireplace, a plate assembly having a casing complementary to the shape of the bar and disposed about the bar, said plate assembly including a plate extension adapted to extend substantially to the bottom of

the fireplace, and a downwardly depending plate member disposed beneath said casing part, said plate member and plate extension including means for anchoring the corner and edge of a flexible screen part thereto.

6. In a fireplace screen of the character described and in combination, a supporting bar having a square shaped main body portion, means at each end of the bar for anchoring the same in position in the opening of a fireplace, a plate assembly having a casing complementary to the shape of the bar and disposed about the bar, said plate assembly including a plate extension adapted to extend substantially to the bottom of the fireplace, a downwardly depending plate member disposed beneath said casing part, said plate member and plate extension including means for anchoring the corner and edge of a flexible screen part thereto, said depending plate member being formed with means for anchoring a chain thereto, a pulley carried by the bar, and a chain passing around said pulley and anchored to said plate assembly.

7. A fireplace screen of the character described comprising a supporting bar, means at each end of the supporting bar for anchoring the same to the walls of a fireplace, a bracket member disposed at each end of the bar, pulleys carried by each of said bracket members, said supporting bar having a square shaped main body portion, a pair of complementary plate assemblies slidably mounted on the square shaped body portion of the bar, flexible screen parts anchored at one edge to said plate assemblies and at the edges which are adapted to be adjacent to the walls of the fireplace by supporting rings that are carried by the bar and immovable thereon, supporting rings movable on the bar intermediate the plate assemblies and the brackets, said supporting rings supporting the screen parts, and a chain passing over said pulleys and being anchored to the plate assemblies whereby the chain is constituted a means for causing opening and closing means of the screen parts.

DANIEL K. EISELE.
